UNITED STATES PATENT OFFICE.

HAMLINE B. WILLIAMS, OF GLENWOOD, IOWA.

CAR-COUPING.

SPECIFICATION forming part of Letters Patent No. 295,706, dated March 25, 1884.

Application filed February 7, 1883. (No model.)

To all whom it may concern:

Be it known that I, HAMLINE B. WILLIAMS, a citizen of the United States, residing at Glenwood, in the county of Mills and State 5 of Iowa, have invented a new and useful Car-Coupling, of which the following is a specification.

My invention relates to improvements in automatic car-couplings or self-couplings; and 10 the objects of my improvement are, first, to reduce the number of pieces composing an automatic car-coupling to the minimum; second, to construct a machine for car-coupling which is self-setting as well as self-coupling, and 15 which is capable of practical use and operation without the presence of any person between the cars while coupling or uncoupling; third, to obviate entirely the danger of personal injuries in car coupling or uncoupling; 20 fourth, to make an automatic car-coupling which can be conveniently used with any coupling in common use; fifth, to permit what are called "flying switches" to be made with perfect safety; sixth, to reduce the time required 25 to make a car coupling or uncoupling to a minimum; seventh, to carry the link in the center of the space in the draw-head when tension is applied, thereby securing the maximum play or freedom of motion; eighth, to 30 prevent uncoupling by the motions of a train; ninth, to obviate the strain upon and tendency to breaking of the link and pin of car-couplings arising from the link being carried on 35 the bottom plate of the draw-head. I attain these objects by the mechanism illustrated in the accompanying drawings, in which—

Figure 1 is a perspective view of that part of the draw-head which projects beyond the dead-wood, showing the top of the automatic 40 pin and the uncoupling device. Fig. 2 is a vertical section of the draw-head and automatic pin or block through the line A B in Fig. 1. Fig. 3 is a vertical section through the lines C D in Fig. 1. Fig. 3½ is a vertical 45 section through the line E F, Fig. 1. Fig. 4 is a side view, in perspective, of the automatic coupling pin or block. Fig. 5, k, is a top view, in perspective, of the beveled slot in the upper plate of the draw-head, in which the automatic pin or block works vertically. Fig. 6 50 is a vertical section of said slot. Fig. 7 is a perspective view of the concave beveled shoulders or projections in the space in the draw-head, which guide the link into position and hold it there for automatic coupling. Fig. 8 55 is a plan of a part of the bottom of the space in the draw-head, showing the beveled groove h, in which the link rests when set for automatic coupling.

Similar letters refer to similar parts throughout the several views.

The draw-head, Fig. 1, is constructed in the common form, (with side couplings to strengthen heavy trains,) except in the following particulars: I make the upper plate thicker than the lower one, to give additional strength at the outer bearing of the automatic pin or block, Fig. 1, c d. I make a slot in said upper plate, Fig. 5, k, an inch wide (more or less) and six inches long, more or less, with the outer end circular, horizontal, or rounded in form, Fig. 5, k, and beveled downward and outward, Fig. 2, r, sufficiently to prevent the pin or block having any tendency to fly out, and enough to give it a slight tendency to slip into the space in the draw-head when tension is applied by the link at the inner end, Fig. 2, i. (I use the terms "inner" and "outer" in speaking of the slot and the pin or block with reference to the ends nearest and farthest from the car, respectively.) The inner end of the slot, Fig. 6, n, is made vertical for a short distance (say half an inch) and then is beveled downward and inward, Fig. 6, j, so that the vertical part forms a bearing for the pin, and the beveled portion of the slot below the vertical part permits the inner end of the automatic pin or block, Fig. 4, a i p, to rise when pressed by the link until the link passes behind it and it drops (working freely vertically in the slot) to make a coupling. The outer end of the slot is made at the usual distance from the end of the draw-head. The draw-bar back of the slot is made in the usual form to fit wood-work and irons already on the car, so that no change of any part except the draw-bar is required to apply my invention. I also use the common buffer or brace on the draw-bar surrounding the inner end of the slot and pin or block, Fig. 1, Z, to prevent the pin 100

or block being forced under the dead-wood, Fig. 1, Y, the same being simply a shelf-shaped vertical projection of iron or other metal, braced as shown in Fig. 1. I use the ordinary appliances for attaching the draw-head to the ear. The draw-head has the common bell-mouth, with three common pin-holes in the bottom plate, Fig. 1, *a a a*, Fig. 8, the two side holes corresponding to holes in the upper plate, 10 and the center hole corresponding with the outer end of the slot, (see Fig. 1,) to allow the removal of the automatic pin or block to make a center coupling with the ordinary link and pin, if necessary. In the bottom plate of the 15 draw-head I make a horseshoe-shaped groove large enough at the curve to receive the link, deepest at the inner curved end of the groove, and running out to the surface of the bottom plate at such an angle as that when the inner 20 end of the link is placed in the groove the outer end will be on a line with the center of and directly in front of the space in the draw-head, Fig. 8, *h*, Fig. 3, *h*, Fig. 2, *h*, Fig. 6, *h*, and Fig. 7, *h*. This groove holds the link in position, and, 25 with the beveled projections hereinafter specified, gives its outer end elevation for automatic coupling. In the inner end or curve of this groove I make a small hole through the bottom of the draw-head, Fig. 8, *g*, to permit the 30 escape of water. This groove runs back to the curved and beveled shoulders or projections inside the space in the draw-head. These shoulders or projections are just far enough back in the draw-head to permit the link to 35 pass freely the lower part of the automatic pin or block. (See Fig. 2, dotted line *l l*, Fig. 3, line *l*, Fig. 6, dotted line *l l*, and Fig. 7, *l l*.) The surface of these projections is shaped something like the upper half of a head-light reflector. They not only curve upward and forward from the edge of the groove in the lower 40 plate to the upper plate, as shown, Fig. 2, *l l*, but also curve across the inner space, as indicated by the line, Fig. 3, *l*. These shoulders 45 or projections, which have an opening between them, Fig. 7, *m*, operate to guide the link directly under the automatic pin or block when two draw-heads come in contact, and also serve to hold the inner end of the link down in the 50 groove *h* and elevate its outer end when placed in position for automatic coupling. They also serve to stop the link and force it under and behind the automatic pin or block in an approaching draw-head. The automatic or self-setting and self-coupling pin or block works 55 freely vertically in the beveled slot in the draw-head. A top view is given, Fig. 1, *d b*, a side view, Fig. 4, and a vertical section, Fig. 2, *a c i*. It can only be put in place by 60 a downward and forward movement, and after inserting the lower part, Fig. 4, *p*, and can only be removed by an upward and backward movement. It falls by its own weight after the link has raised it and passed back of its 65 inner end, and effects a coupling. If two draw-heads are brought rapidly together, the coup-

ling is facilitated by the rebound of the pin from the inner end of the beveled slot. Working freely in the slot, it is constantly set automatically and couples automatically. It may 70 be made of cast-iron, cast-steel, malleable iron, aluminium, or other cast or wrought metal. Common cast-iron is amply strong. A portion of its outer end, Fig. 4, *q*, is fitted to the outer circular beveled end of the slot in the 75 draw-head. Its outer end does not extend below the upper plate of the draw-head. It is beveled from its outer end to where it rests on the lower plate of the draw-head, is coincident with the lower plate for an inch (more or 80 less) to the point *p*, when it is made with a bevel upward and forward, as shown by the line *i p*, Fig. 4. Both ends of the pin are made rounding horizontally, to prevent the wear of the pin or block and link interfering with a free vertical 85 motion in the slot. At such a point, Fig. 2, *i*, on the inner end of said automatic pin or block as will insure the link being carried about in the center of the space in the draw-head when tension is applied, I make a shallow groove or 90 depression, into which the force of a pull draws the link sliding up the beveled line *i p*. This serves not only to give the link all the "play" or freedom of motion which the space in the draw-head will admit of, but also distributes 95 the resistance offered by the pin in the direction of the dotted lines, Fig. 2, *i r i s*, rendering it practically impossible to break the automatic pin or block. I make that portion of the automatic pin or block which is above the 100 upper plate of the draw-head when it is in position for automatic coupling, Fig. 1, *a b c d*, Fig. 2, *a o*, project over the sides and ends of the slot, and fit closely to the upper surface of the draw-head, as shown in Fig. 5, dotted line 105 *v*, and beveled at the outer end, as shown in Fig. 4, *c*. These projections of the pin or block serve to hold it in its proper position for automatic coupling to resist any tendency of the outer end to slip into the draw-head when 110 tension is applied, and also serve as a roof to keep snow, sleet, cinders, &c., out of the slot. This projection is beveled upward and outward at the outer end, Fig. 2, *c*, to prevent the outer end of the pin rising in uncoupling. 115 At or near the inner end of the automatic pin or block, and on the upper surface thereof, I make a vertical projection, Fig. 1, *a*, Fig. 4, *a*, in which is a hole to receive a short chain or rod, Fig. 1, *a f*, used in uncoupling. The 120 uncoupling is accomplished by raising the inner end of the automatic pin or block vertically (the arm of the uncoupling device over the pin being made long enough to extend slightly beyond the hole in the projection, so 125 as to have a tendency to throw the pin against the outer end of the slot) until it strikes the inner end of the beveled slot in the draw-head. When in this position, the lower part, Fig. 4, *p*, of the pin or block is above the space in the 130 draw-head, permitting the link to pass out, and at the same time the automatic pin or

block is incapable of any movement whatever except to fall back into the position shown by its section in Fig. 2, set ready for coupling. The uncoupling may be done by hand or by a device substantially like that shown in Fig. 1, 5 *ee, ee, ff, ff*, with the chain or rod *a f* attached to the arm *ff* of the uncoupling device over the pin or block and the chain or rod *ft*. In Fig. 1, *ee ee* represent a common rod, 10 of iron or other metal, sufficiently large to be practically stiff, attached to the body of the car immediately over the dead-wood and below the car-floor by common staples, in which it turns freely. One staple is driven each side 15 of and close to the arm *f* over the pin or block, Fig. 1, *u*, to keep the rod *ee* in position. At or near the sides of the car I bend the ends of the rod *ee ee* vertically downward at about a right angle, forming a lever or handle by 20 which to uncouple from either side of the car, obviating the necessity of going between cars for that purpose. The arms *ff* may be welded to the rod or attached by set-screws. On a platform-car the short arm *ff* is not required. 25 The chain or rod *ft* runs to the top of a box-car, where it may be worked, if desired, by a short foot-lever attached to the edge of the car-roof. It may also end at *t* in a loose ring passed over the rod of the brake-wheel, or otherwise 30 conveniently attached to the car-roof. If a rod is used instead of a chain, *ft*, it may be bent from a convenient point on the end of the car to the eye of the short arm *ff*, to which it may be attached by a hook. The rod *ee ee* 35 is attached far enough below the car-floor so that projecting timber or rails will not interfere with the uncoupling device, and the short arm *ff* is placed sufficiently near the side of the car so that the rod or chain will clear the 40 end door of the car, if any.

I use a link of the common form and size, except that it is made enough longer to reach behind the automatic pin or block. This extra length is carried in the draw-heads, so that 45 the draw-heads are the usual distance apart, permitting use of the side couplings. The link is set for automatic coupling by simply thrusting it into the draw-head as far as it will go.

The inner end will then be down in the groove *h* and held there by the beveled shoulders *l*, 50 while the outer end will point to the center of the space in an opposite draw-head. The link will usually be set in the stationary car, though for short runs it will not jar out of position in a moving car.

The broken places in the rod at the end of the dead-wood *Y* indicate greater length than is shown in the drawings, the end of the car not being shown.

I am now aware that prior to my invention 60 car-couplings have been made with coupling pins or blocks or lever-catches operating vertically in a slot in the draw-head, and also that triple draw-heads have been made. I do not therefore claim such a combination, broadly, but only as hereinafter contained.

I am also now aware that prior to my invention uncoupling mechanisms consisting of lever engagements have been made. I do not therefore claim such a combination, broadly; 70

What I do claim as my invention, and desire to secure Letters Patent for, is—

1. The bell-mouthed draw-head, Fig. 1, with triple pin-holes *o* and beveled slot *h*, adapted 75 to receive the lever-catch or automatic block, with beveled horseshoe-shaped groove in the lower plate, *w*, with water-hole *y*, with shoulders or projections *l* in the chamber or cavity, with the upper plate thicker than the lower, 80 with longitudinal opening *m*, with brace *Z*, all constructed substantially as described.

2. The combination of the automatic pin, 85 block, or lever-catch, Fig. 4, with the triple-slotted draw-head, Fig. 1, all constructed substantially as described.

3. The combination of the automatic pin, block, or lever-catch, Fig. 4, with the triple-slotted draw-head, Fig. 1, and uncoupling mechanism, all constructed substantially as 90 described.

HAMLINE B. WILLIAMS.
